CLAIM

The ornamental design for a half-high disk drive tray bezel, as shown and described.

DESCRIPTION

FIG. 1 is a top front and left side perspective view of the disk drive tray bezel showing our new design, and a tray and spring contacts depicted in broken lines for illustrative purposes only which form no part of the claimed design; and,

FIG. 2 is a top front and right side perspective view thereof. The areas of the tray which have not been completely disclosed in FIG. 1 and FIG. 2 are understood not to be part of the claimed design.
